Primary Examiner — Philip S Hyder(74) *Attorney, Agent, or Firm* — Global IP Counselors, LLP(57) **CLAIM**

The ornamental design for a discharge device, as shown and described.

DESCRIPTION

FIG. 1 is a perspective top side view in accordance with our new design;

FIG. 2 is a left side view thereof;

FIG. 3 is a right side view thereof;

FIG. 4 is a front view thereof;

FIG. 5 is a back view thereof;

FIG. 6 is a top side view thereof; and,

FIG. 7 is a bottom side view thereof.

The broken lines shown in the drawings depict portions of the invention that form no part of the claimed design.
